CONDIMENT DISPENSER

John W. Kuhn, Deerfield Beach, Fla.

Application October 24, 1956, Serial No. 618,014

9 Claims. (Cl. 222—457.5)

This invention relates to a dispensing receptacle and more particularly to an improved condiment dispenser for granulated substances such as sugar, salt, pepper and the like and is directed primarily to an apparatus for retaining such products in a normally dry and free-flowing condition.

The primary object of this invention resides in the provision of a sealing means so designed as to reduce and eliminate the normal clogging of a dispenser due to the moisture absorbing qualities of the condiment products by permitting the condiment to be exposed to the surrounding atmosphere only during the actual discharge of the same from the dispenser.

Another important object of the present invention is the provision of a dispenser of this characteristic having a delivery conduit extending downwardly into the interior of the receptacle and employing a novel and improved gravity-actuated valve assembly which is normally retained in a closed position to prevent moisture that may be trapped within the delivery conduit from entering the interior of the receptacle and which will be actuated to an open position when the dispenser is inverted allowing the contents to flow therefrom.

A further object of the present invention is to provide a gravity-actuating, self-closing condiment dispenser having a flow-restricting valve cooperating with the sealing means and operating in response to the opening movement thereof for controlling the quantity of condiment delivered to the delivery conduit.

A still further object of the present invention is to provide a condiment dispenser with a delivery conduit having sealing surfaces located in the upper and lower portions thereof and sealing means operably disposed in said upper and lower portions simultaneously cooperating with said sealing surfaces for normally closing the same to prevent moisture from entering either the conduit or the interior of the dispenser.

Another object of the invention is to provide a device which can be used in conjunction with the usual form of condiment receptacle, and which can be readily applied thereto and removed therefrom for cleaning and the like.

A still further object of the present invention is to provide a dispenser of this character which is extremely simple in construction, thoroughly reliable and effective in its purpose, neat and attractive in its appearance, readily and easily operable for dispensing purposes, thoroughly sanitary, possessing but few parts, relatively inexpensive to manufacture, and otherwise well adapted for the purposes for which the same is intended.

Other objects and the entire scope of the present invention will become apparent from the detailed description given hereinafter. It should be understood, however, that the detailed description and specific examples, while indicating the preferred embodiments of the invention, are given by way of illustration only, since various changes and modifications within the spirit and scope of the invention will become apparent as the description herein progresses.

2

Reference being made to the accompanying drawings forming part hereof, wherein like numerals refer to like parts throughout, and in which:

5 Figure 1 is a longitudinal vertical sectional view taken through the condiment dispenser constructed in accordance with the present invention, and with parts of the dispenser removed therefrom;

10 Figure 2 is a similar view of Figure 1, and showing the dispenser inverted to actuate the valve assembly to an open position;

15 Figure 3 is a longitudinal vertical sectional view taken through the condiment dispenser with parts removed therefrom showing another form of the novel valve assembly;

20 Figure 4 is a fragmentary elevational view of the delivery conduit formed as an integral part of the cap and adapted to be used with the dispenser body shown in Figure 1;

25 Figure 5 is a view in vertical longitudinal section of the delivery conduit used in conjunction with the present invention;

30 Figure 6 is a perspective view illustrating a modified form of the valve assembly constructed in accordance with the present invention; and

35 Figure 7 is a fragmentary elevational view of the valve assembly shown in Figure 1.

Referring now to the drawings in detail, wherein for the purposes of illustration, there is described a preferred embodiment of the present invention, the numeral 10 represents a closure or dispenser cap of a non-corrosive material having a preferably conical upper end portion 12 that is provided with a centrally located aperture 14 communicating with the interior of the cap 10. The cap interior is shaped to define a hollowed and substantially conical discharge chamber 11 which is formed above the threaded neck engaging section 16 of the cap.

40 A hollow body or container 18 which constitutes a receptacle for the contents 20 is shown in this instance made of glass, although it may be made from any other suitable material such as plastic or the like, and is preferably of the shape disclosed in Figure 1 of the drawings. The body 18 has an upper neck portion 22 with an opening 24 extending therethrough. The neck portion 22 is externally threaded as at 26 to detachably receive the cap neck engaging section 16.

45 Arranged within the lower part of the discharge chamber 11 is a generally cylindrical conduit 28 having a substantially uniform bore 29 throughout the major length thereof. The delivery conduit 28 extends downwardly through the neck opening 24 and terminates within the body 18 to provide communication between the interior of the body and the discharge chamber 11. Extending outwardly from the upper end of conduit 28 is an annular supporting flange 30 which is removably mounted between the annular shoulder 13 formed in cap 10 and the upper

50 surface 32 of the delivery conduit 28, as shown. The upper portion 32 of the delivery conduit has an outlet or upper sealable orifice 34 opening into the discharge chamber 11. The outlet 34 is flared outwardly to form a conical sealing surface or valve seat 38. The lower portion 31 of the delivery conduit diminishes slightly in cross-section to form an inlet or lower sealable orifice 36 having an annular sealing surface or valve seat 37. The conduit 28 terminates below the sealable orifice 36 to form an outwardly flared conical flange 42 which communicates with the interior of the body 18.

55 In Figure 4, the delivery conduit 27 is formed as an integral part of the cap 15 and is adapted to be used with the dispenser body 18 shown in Figure 1. This unitary structure is preferably molded from a plastic material

60 and may be adapted to fit the usual type of condiment container.

65 70

A sealing means comprising a valve assembly 40 is slidably disposed within the delivery conduit 28 normally sealing both the inlet 36 and the outlet 34; said valve assembly being operable to open the same, allowing the contents to flow into the discharge chamber 11. The valve assembly 40 includes a longitudinally extending stem or shaft 42 which is positioned axially within the conduit 28. The stem 42 carries an upper valve member 44 and a lower double-acting valve member 46. The upper valve member 44 is located within the discharge chamber 11, and is adapted to normally seat against the conical sealing surface 38, while the lower double-acting valve member 46 includes a primary valve 48 and a secondary, flow-restricting valve 50. The primary valve 48 is located completely within the delivery conduit 28 and normally seats against the valve seat 37, to seal the conduit inlet 36, and is of a size to permit passage of the contents around the same into the conduit 28 when the dispenser is in an inverted position. Thus it will be noted that the upper and lower valve members 44 and 48, simultaneously cooperate with the valve seats 38 and 37 respectively for normally closing both the outlet 34 and inlet 36 to prevent the entrance of moisture into either the conduit 28 or the interior of the body 18. Moreover, the novel arrangement of these valves prevents moisture that may be trapped within the conduit 28 from entering the interior of the receptacle. Accordingly, the contents 20 are exposed to the surrounding atmosphere only during the actual discharge of the same from the dispenser when inverted.

An additional flow-restricting valve 50 may be employed to regulate the quantity of material delivered to the inlet 36. The valve 50 has a diameter slightly less than the minimum cross-sectional area of the delivery conduit inlet 36 and is suspended exteriorly therefrom in a normally non-restrictive position. When the dispenser is inverted, actuating the valve assembly 40 to an open position, the valve 50 also moves in response to the opening movement thereof to restrict the flow of condiments through the inlet 36.

The stem 42 may be extended upwardly through the discharge chamber 11 and terminated adjacent the aperture 14 to support a discharge assistant 52. The discharge assistant 52 is of a size to pass outwardly through the aperture 14 in cooperation with the opening movement of the valve assembly 40 for dislodging any condiments collected around the aperture and adhering to the cap.

Rigidly attached to or forming an integral part of the upper valve member 44 and the stem 42, are a plurality of circumferentially-spaced fins or vanes 54, projecting upwardly from the valve member 44. The side edges 56 of the fins 54 are spaced from the inner wall of the chamber 11 to permit axial movement of the valve assembly 40. In the dispensing operation, the upper edges 58 of the fins 54 abut against the interior conical portion 60 of the cap 10 to limit the opening movement of the valve assembly 40 in one direction.

A modified form of conduit and valve assembly is illustrated in Figure 4 of the drawings. In this construction, the conduit 27 is formed integrally with the cap 15 and the valve assembly includes upper and lower valve members 45 and 47 respectively which are supported by a longitudinally extending valve stem 43. The upper valve member 45 has a reduced lower portion 49 which embraces and forms a seal with the concavo-convexed valve seat 39 in the upper portion of the delivery conduit 27. The lower portion 49 of the valve 45 also serves as a deflector for the falling salt, so that salt accumulation will have little opportunity to attach to the cap 15, thus keeping the cap surface relatively clean and sanitary, to ensure sealing with the valve seat 39 and closing of the conduit outlet 33. The lower valve member 47 serves to normally seal the conduit inlet 35. The valve stem 43 carries a cross-member 61 positioned between the upper and lower

valve members which serves to retain the upper valve member 45 in a central position when open, and the stem 43 extends outwardly through the inlet opening and is bent to form a movement-limiting hook 59 at a right angle thereto which contacts the lower terminal portion 62 of the conduit 27 upon opening movement of the valve assembly. In addition, a flow-restricting valve 50 may be carried by the stem 43 between the lower valve member 47 and the movement-limiting hook 59 for controlling the quantity of intake in response to said opening movement.

It is to be understood that the valve assembly 40 may consist of merely upper and lower sealing valves as shown in Figure 3, or include a double-acting lower-valve member as illustrated in Figure 7. Moreover, a discharge assistant may be added to the assembly as disclosed in Figure 6. The previously discussed features may be incorporated into a single assembly, similar to Figure 7 of the attached drawings, in accordance with the purposes of the present invention.

An advantage of a condiment dispenser constructed in accordance with the present invention resides in the fact that all of the components may be individually molded of plastic material in finished form and readily assembled by first filling the hollow body portion 18 with the desired condiment; inserting the delivery conduit 28 through the neck opening 24 into the interior of the body; sliding the integrally molded valve assembly 40 into the conduit 28, and securing the cap 10 to the body 18 in the conventional manner.

It should be noted that the valve assembly 40 may be integrally molded from plastic material with a wire or cord reinforcement 41 passing longitudinally through the stem 42. This reinforcement of the stem 42 permits the same to be relatively small, thereby allowing the conduit bore 29 to be further reduced in diameter.

It is also to be understood that, although several preferred embodiments of the invention have been shown in the drawings and described with considerable particularity in the foregoing specification, the invention is not limited to the specific details of construction, shown and described, but includes all modifications coming within the scope of the appended claims and their equivalents.

I claim:

1. A condiment dispenser comprising a hollow body provided with a neck portion at one end having an opening therethrough, a cap for the body including a neck engaging section; said cap having a dispensing aperture formed therein, a delivery conduit positioned within said neck opening having an upper portion mounted in cooperation with said cap and a lower portion extending downwardly through said opening to provide communication between the interior of the body and said aperture; said conduit having a substantially uniform bore throughout the major length thereof, said bore diminishing slightly in cross-section adjacent said lower portion and flaring outwardly adjacent said upper portion to define annular sealable orifices, and sealing means operably disposed in said upper and lower portions simultaneously cooperating with said orifices for normally sealing the same to prevent the entrance of moisture into said conduit and the interior of said body.

2. A condiment dispenser as set forth in claim 1 wherein said sealing means includes a plurality of cooperating valves normally closing the upper and lower portions of said conduit against the entrance of moisture and simultaneously operable to open the same allowing passage therethrough of the dispenser contents.

3. The combination of claim 2 and means for maintaining said sealing means in axial alignment with said delivery conduit upon opening movement thereof.

4. The structure as set forth in claim 3 and motion-limiting means for limiting the opening movement of said sealing means in one direction.

5. The combination of claim 2 and a flow-restricting

valve disposed adjacent the lower portion of said conduit cooperating with said sealing means, said flow-restricting valve being operable in response to the opening movement of said sealing means for controlling the quantity of condiment delivered to said conduit.

6. A condiment dispenser comprising a hollow body provided with a neck portion at one end having an opening therethrough, a cap for the body having detachable connection therewith and including a centrally located dispensing aperture formed therein, a generally cylindrical delivery conduit removably mounted between said neck portion and said cap and extending downwardly therefrom through said neck opening to provide communication between the interior of the body and said aperture, said conduit having an outlet spaced below said aperture to define a discharge chamber therebetween and an inlet located at the opposite end thereof, a valve assembly slidably disposed within said conduit for normally sealing said inlet and outlet against the entrance of moisture and operable to simultaneously open the same for allowing the contents to pass therethrough, a flow-restricting valve extending from the lower portion of said assembly through the conduit inlet for controlling the quantity of intake in response to the opening movement of said valve assembly, and a discharge assistant extending from the upper portion of said assembly terminating adjacent said aperture, said discharge assistant being of a size to pass outwardly through said aperture in cooperation with said assembly opening movement for dislodging any contents adhering to the cap.

7. A condiment dispenser comprising a hollow body provided with a neck portion at one end having an opening therethrough, a cap for the body having detachable connection therewith and including a centrally located dispensing aperture formed therein, a generally cylindrical delivery conduit removably mounted between said neck portion and said cap and extending downwardly therefrom through said neck opening to provide communication between the interior of the body and said aperture, said conduit having an outlet spaced below said aperture to define a discharge chamber therebetween and an inlet

5 located at the opposite end thereof, said conduit having a substantially uniform bore throughout the major length thereof, said bore diminishing slightly in cross-section adjacent the inlet and flaring outwardly adjacent the outlet to form valve seats, a valve assembly slidably disposed within said conduit for normally sealing said inlet and outlet including a longitudinally extending stem positioned axially therethrough, an upper valve member carried by said stem and located within said discharge chamber for normally seating against the outlet valve seat and a lower double-acting valve member having primary and secondary valves carried by said stem, said primary valve being located within the delivery conduit for normally seating against the inlet valve seat and of a size to permit passage of the contents around the same into said conduit when in open position, said secondary valve being suspended exteriorly of the conduit inlet permitting a flow of contents therethrough when in normal position and operable to restrict the flow of the same upon opening movement of said primary valve.

located at the opposite end thereof, said conduit having a substantially uniform bore throughout the major length thereof, said bore diminishing slightly in cross-section adjacent the inlet and flaring outwardly adjacent the outlet to form valve seats, a valve assembly slidably disposed within said conduit for normally sealing said inlet and outlet including a longitudinally extending stem positioned axially therethrough, an upper valve member carried by said stem and located within said discharge chamber for normally seating against the outlet valve seat and a lower double-acting valve member having primary and secondary valves carried by said stem, said primary valve being located within the delivery conduit for normally seating against the inlet valve seat and of a size to permit passage of the contents around the same into said conduit when in open position, said secondary valve being suspended exteriorly of the conduit inlet permitting a flow of contents therethrough when in normal position and operable to restrict the flow of the same upon opening movement of said primary valve.

8. The condiment dispenser as set forth in claim 7 wherein said valve assembly includes a plurality of circumferentially-spaced fins projecting upwardly from said upper valve member, said fins being slidably confined within said discharge chamber and adapted to abut against the interior of said cap to limit the opening movement of said valve assembly.

9. The structure as set forth in claim 7 wherein said valve assembly includes a plurality of circumferentially-spaced fins projecting upwardly from said upper valve member, said fins being slidably confined within said discharge chamber and adapted to abut against the interior of said cap to limit the opening movement of said valve assembly.
